CLAIM

The ornamental design for a shuffle for optically connecting nodes and devices, as shown and described.

DESCRIPTION

This application is related to the following U.S. Design application Ser. Nos. 29/741,755, 29/741,764, 29/741,777. FIG. 1 is a first embodiment of an upper, right side perspective view of the shuffle for optically connecting nodes and devices;

FIG. 2 is a lower, left side perspective view of the first embodiment thereof;

FIG. 3 is a front side view of the first embodiment thereof;

FIG. 4 is a back side view of the first embodiment thereof;

FIG. 5 is a left side view of the first embodiment thereof;

FIG. 6 is a right side view of the first embodiment thereof;

FIG. 7 is a top plan view of the first embodiment thereof;

FIG. 8 is a bottom plan view of the first embodiment thereof;

FIG. 9 is a second embodiment of an upper, right side perspective view of the shuffle for optically connecting nodes and devices;

FIG. 10 is a lower, left side perspective view of the second embodiment thereof;

FIG. 11 is a front side view of the second embodiment thereof;

FIG. 12 is a back side view of the second embodiment thereof;

FIG. 13 is a left side view of the second embodiment thereof;

FIG. 14 is a right side view of the second embodiment thereof;

FIG. 15 is a top plan view of the second embodiment thereof; and,

FIG. 16 is a bottom plan view of the second embodiment thereof.

The broken lines and shade lines do not form part of the claimed design.

1 Claim, 12 Drawing Sheets
